(57) **CLAIM**

We claim the ornamental design for a scoring knife, as shown.

DESCRIPTION

FIG. 1 is a perspective view of a scoring knife, embodying our new design;

FIG. 2 is a front side view of the scoring knife of FIG. 1. FIG. 3 is a back side view of the scoring knife of FIG. 1. FIG. 4 is a left side view of the scoring knife of FIG. 1. FIG. 5 is a right side view of the scoring knife of FIG. 1. FIG. 6 is a top side view of the scoring knife of FIG. 1; and, FIG. 7 is a bottom side view of the scoring knife of FIG. 1. The broken lines depict portions of the scoring knife in which the design is embodied that are not considered part of the claimed design.
